(57) **CLAIM**

The ornamental design for a tire, as shown and described.

DESCRIPTION

FIG. 1 is a perspective view of a tire of our new design, it being understood that the tire could have a retread tire tread or have a new tire tread, and that the tread is repeated uniformly throughout the circumference of the tire.

FIG. 2 is a front view of the embodiment of FIG. 1.

FIG. 3 is a right side view of the embodiment of FIG. 1.

FIG. 4 is a left side view of the embodiment of FIG. 1.

FIG. 5 is a cross-sectional view taken along line 5-5 of FIG. 2.

FIG. 6 is a cross-sectional view taken along line 6-6 of FIG. 2.

FIG. 7 is a perspective view of a second embodiment of a tire of our new design, it being understood that the tire could have a retread tire tread or have a new tire tread, that the tread is repeated uniformly throughout the circumference of the tire, and that the broken lines show environmental features of the tire that form no part of the claim.

FIG. 8 is a front view of the embodiment of FIG. 7.

FIG. 9 is a right side view of the embodiment of FIG. 7.

FIG. 10 is a left side view of the embodiment of FIG. 7.

FIG. 11 is a cross-sectional view taken along line 11-11 of FIG. 8; and,

FIG. 12 is a cross-sectional view taken along line 12-12 of FIG. 8.
